UNITED STATES PATENT OFFICE.

JACOB PLATT, OF BROOKLYN, NEW YORK, ASSIGNOR OF ONE-HALF TO JESSE SATEN-STEIN, OF NEW YORK, N. Y.

BOOKBINDING APPARATUS.

1,289,902.

Specification of Letters Patent. Patented Dec. 31, 1918.

Application filed February 26, 1918. Serial No. 219,220.

To all whom it may concern:

Be it known that I, JACOB PLATT, a citizen of the United States, and a resident of the borough of Brooklyn, county of Kings, 5 city and State of New York, have invented certain new and useful Improvements in Bookbinding Apparatus, of which the following is a specification.

My improvements relate to so called 10 "case" machines in which the side boards are applied to the covering, as in Letters Patent No. 513,453, of January 23, 1894, for machine for making book covers, Letters Patent No. 580,111, of April 6, 1897, for 15 machine for making book covers, and Letters Patent No. 661,763, of November 13, 1900, for book cover machine, and the object is to insure the accurate alinement and delivery of the superposed covering and side 20 boards to the press mechanism which effects their final attachment to each other. Heretofore much loss and inconvenience has resulted from the lack of adequate lateral control of the cover while being fed to the press 25 table, the edges of the boards frequently contacting with side walls of the press, causing the buckling and distortion of the cover, and rendering it not only useless but necessitating the stopping of the 30 apparatus in order to effect its removal.

I obviate this difficulty by my invention which consists essentially in the provision of yielding rockable guards which control and sustain the edges of the covering until 35 the latter is well advanced upon the press platen, and between, and in substantial parallelism with, the side members thereof, all as hereinafter more fully set forth.

In the accompanying drawings I show 40 correlated parts of what is known in the book binding trade as a "case" machine, sufficient to illustrate the practical embodiment of my invention in apparatus of the character designated, other parts of the 45 machine being omitted.

Figure 1 is a plan of a "case" machine of ordinary and well known construction;

Fig. 2 is a partial sectional elevation taken upon plane of line 2-2, Fig. 1; 50 Fig. 3 is an elevation of a portion of the machine, looking in the direction of the arrow 3, 3, Fig. 1;

Fig. 4 is a diagram upon a smaller scale illustrating in dotted lines the transfer of

the cover blank from the assembling table 55 to the press platen;

Fig. 5 is a sectional elevation showing one of the guides;

Fig. 6 is a top view of the same;

Fig. 7 is a top view of the rear guide; 60

Fig. 8 is a view similar to Fig. 5, showing a modification;

Figs. 9 to 13 inclusive illustrate successively the action of the forwarder in depressing the lateral guides while transferring the cover blank from the assembling table to the press platen; 65

Fig. 14 is a view similar to Fig. 11, showing a slight modification in the means of supporting the lateral guides; 70

Fig. 15 is a view similar to Fig. 14, showing another modification.

F, represents the feed cylinder and f, the gage fingers by which the cover-sheet, with an adhesive applied to the side that becomes 75 the inner face thereof, is presented to the pinching action of the grippers g, g, which latter act in conjunction with the reciprocating bar g', on which they are mounted to transfer said cover-sheet from said cylinder F, to the assembling table A, in the usual manner. H, represents the ordinary swinging suction head by which the side boards of the cover are lifted and transferred from the table h, to the adhesive upper 80 side of the cover-sheet on the assembling table A in a manner well known in the art. D, is the reciprocatory "discharge head" or forwarder by which the cover-sheet S, with the side boards b, b, (see Fig. 4) imposed 85 thereon, is transferred from the assembling table A, to the usual water cushion platen p, of the ordinary press mechanism P, by which the cover-sheet S, and boards b, b, are made to adhere in smooth relationship,— 90 p', p', representing the usual barbed feed and discharge disks, p², the pressure plate, and p³, the actuating toggles, all of ordinary construction and operation.

The reciprocation of the forwarder D, is 100 accomplished by the usual endless belt and cam mechanism indicated generally by the letter d, in the first three figures of the drawings. The press mechanism is operated in the usual way by the rod p⁵, actuated by 105 the cam Q, Fig. 3.

In practical operation the grippers g, g, sometimes fail to take even hold of the edge

of the cover-sheet S, presented by the gage fingers f,—resulting in the deposit of the sheet S, in bad shape on the assembling table A; and the side cover boards b, b, are sometimes warped so that the forwarder D, cannot control them effectually. As a result of one or the other or both of these causes, the cover blank is apt to contact with the inner extremity (p^x) of one or the other of the side members p⁴, which flank the platen p, of the press mechanism P, thereby buckling up and distorting the cover blank, rendering it useless, and (what is of even more consequence) clogging the apparatus, which means the stoppage of the machine until the obstruction can be removed. In fact this is one of the serious defects of this type of "case" machine, representing a problem heretofore unsolved in a practical manner.

I accomplish the desired result by my yieldable and rockable lateral guards R, R, one positioned at the front side, and the other at the rear side, of the assembling table A, as shown in Fig. 1, by reference to which it will also be seen that these guards R, R, are likewise both positioned well within the planes of the inner sides of the side members p⁴, which flank the press platen p, thus reducing the chance of possible contact of the cover blank S, b, b, with the inner corners p^x, p^x, of said side members p⁴.

But the main feature of my invention consists in rockably mounting the lateral guards R, R, in such manner that their inner extremities control the cover blank beyond the points of pivotal support of said guards and until the advancing edge of the cover blank is upon the platen p, and well beyond the inner ends p^x, of the side members p⁴, of the platen frame.

To accomplish this result the inner end r, of each lateral guard R, may be mounted snugly but movably (as in Figs. 5, 6 and 7) in a transverse slot c, formed for it by preference in a cap block C, attached to the framework of the apparatus between the position of the assembling table A, and the press platen p, as shown more particularly in Figs. 1 and 2. Said inner ends r, of the lateral guards R, are retained within said slots c, by means of pins c', c², passing through slots r', r', formed for them in the guards R, said pins c', c², being driven into position through the end of the cap block C. In this construction spiral springs c³, c³, are seated in recesses c⁴, c⁴, formed for them in the cap block (see particularly Fig. 5) and bear against the under edges of the lateral guards R, tending constantly to hold the latter in elevated horizontal extension as shown in Figs. 5 and 9, with the pins c', c², occupying the bottoms of the slots r', r'. A like result is attained in the modification shown in Fig. 8, in which a single U-spring c³³, is substituted for the twin coil springs

c³, c³, shown in Fig. 5,—the guard R, in Fig. 8, being mounted on the end of the cap block C, and being held thereto by the heads of the screws c'', c'', the shanks of which extend through the slots r', r', in the guard R, and form the equivalent of the pins c', c², shown in Fig. 5. It is to be understood that in Figs. 9 to 15 inclusive the spring supports for the inner ends of the guards R, are omitted for simplicity and clearness of illustration, Figs. 5 and 8 being relied upon to indicate the principle of resilient support involved.

In either case the springs afford yielding supports which tend constantly to hold the lateral guards in normal position, but allow them to be depressed by the forwarder D, as it advances with the cover blank in front of it,—the outer or free ends r², of the lateral guards R, being of course curved downward to allow the forwarder D, to contact with and depress the guards R, gradually, as in Figs. 9 and 10. As will be understood by reference to Figs. 10 and 11, the guard R, rocks on the rear pin c', until the forwarder D, has passed the first pin c², as in Fig. 12, when the rear end of the guard is depressed, but this rear depression does not occur until the advancing end of the cover blank S, has passed onto the press platen p, and beyond the edges p^x, p^x, of the side members p⁴, p⁴, of the press frame, as shown in dotted lines in Fig. 4, thereby obviating all danger of serious lack of alinement of the cover blank, and insuring its presentation to the press mechanism in due form.

It will be noted in this connection that it is the rear pins c', which perform the important function, in conjunction with the resilient support below, of pivotal guides for the rear portions r, of the lateral guards R, until the forwarder D, has advanced sufficiently to depress said rear portions r, of the guards R. This will be understood by a comparative examination of Figs. 9 to 13 inclusive, by which it will be seen that until so finally depressed by the forwarder D, the rear portions r, of the guards R, protrude above the plane of the advance of the cover blank and hence obviously safeguard the latter until well on its way to and partly upon the press platen p, as above set forth. And this protrusion of the rear portions r, of the guards R, until the safe passage of the cover blank is assured, is the distinctive feature of my invention, effected by the resilient support and by the rear slots r', controlled by the pins c'. Hence, obviously, a like result may be attained by the modification shown in Fig. 14, in which the forward slot r'', and pin c², are omitted, a stop r³, on the guard R, being substituted for the pin c²,—said stop r³, contacting with a shoulder c³, or equivalent, on the cap block C, when the guard is raised to normal hori-

zontal position by the spring pressure after the forwarder D, is retracted. In other words, the rear slots r', and the resilient support afforded the rear portions r, of the 5 lateral guards enable the latter to control the cover blank until the main portion thereof is beyond such points (c') of pivotal support of the guards,—a result not heretofore attained in the art, and an important one for 10 the reasons heretofore set forth.

It is obvious that like results can be attained by affixing the fulcrum pin c', to the rear portion r, of the guard R, and by forming the equivalent of the slot r', in the side 15 walls of the transverse slots c, as indicated in Fig. 15, so that I do not limit myself in this respect, the essential features being the resilient support for the rear portions of the guards, as illustrated in Figs. 5 and 8, and 20 the slot and pivot connection of parts which admits of the rockable depression of the guards as and for the purpose set forth.

What I claim as my invention and desire to secure by Letters Patent is,

25 1. In book binding apparatus of the character designated, in combination with the assembling table and press platen, and with the mechanism for transferring the cover blank from said assembling table to said 30 press platen, yieldable and rockable lateral guards flanking the path of transfer and normally protruding above the plane thereof, for the purpose described.

2. In book binding apparatus of the character designated, in combination with the assembling table and press platen, and with the mechanism for transferring the cover blank from said assembling table to said 35 press platen, lateral guards flanking the path of transfer and normally protruding above the plane thereof, the rear portion of each guard resting on a resilient support, and being pivotally controlled by means 40 which admit of the depression of the said 45 lateral guards by the said transfer mechanism, for the purpose described.

3. In book binding apparatus of the character designated, in combination with the

assembling table and press platen, and with the mechanism for transferring the cover blank from said assembling table to said press platen, lateral guards flanking the path of transfer and normally protruding above the plane thereof, the rear portion of each guard resting on a resilient support and 55 being formed with a transverse slot, and a retaining pin extending through said slot, for the purpose described.

4. In book binding apparatus of the character designated, in combination with the assembling table and press platen, and with the mechanism for transferring the cover blank from said assembling table to said press platen, lateral guards flanking the path of transfer and normally protruding above the plane thereof, the rear portion of each guard resting on a resilient support and 60 being formed with a transverse slot, and a retaining pin extending through said slot, together with means acting in conjunction 65 with the said transverse slot and retaining pin to limit the upward thrust of the forward portion of the guard while admitting 70 of the depression thereof, for the purpose described.

5. In book binding apparatus of the character designated, in combination with the assembling table and press platen, and with the mechanism for transferring the cover blank from said assembling table to said 75 press platen, lateral guards flanking the path of transfer and normally protruding above the plane thereof, the rear portion of each guard resting on an elastic resilient support and being fulcrumed on a pivot 80 passing through a slot elongated to allow the guard to be depressed, together with means acting in conjunction with said transverse slot and pivot to limit the upward 85 thrust of the forward portion of the guard 90 while admitting of the depression thereof, for the purpose described.

JACOB PLATT.
